COMPUTOR FOR ORDNANCE DATA

Raymond E. Crooke and Willard B. Constantines, Great Neck, N. Y., assignors to Ford Instrument Company, Inc., Long Island City, N. Y., a corporation of New York

Application September 14, 1945, Serial No. 616,230

7 Claims. (Cl. 235—61.5)

1

This invention relates to automatic computing mechanism for fire-control purposes and has for an object to provide a device of the above type having novel and improved operating characteristics.

A feature of the invention is the provision of computing mechanism including rotatable shafts which are driven at controlled rates proportional to the computed data. Sine and cosine functions are introduced by trigonometric integrators of the driven ball type and the rates of the output shafts are measured by mechanical tachometers of the integrator type. A motor provides the power for driving the rotating shafts and the various integrators.

Although the novel features which are believed to be characteristic of this invention are pointed out more particularly in the claims appended hereto, the nature of the invention will be better understood by referring to the following description taken in connection with the accompanying drawing in which a specific embodiment has been set forth for purposes of illustration.

In the drawing the figure is a diagrammatic representation of a computing mechanism embodying the present invention.

Referring to the drawings more in detail the invention is shown as embodied in a computing mechanism which derives elevation and train data from gearing actuated by an elevation rack 10 and a train rack 11 associated with the gun, or which are otherwise driven so that the movements of the gearing correspond to the elevation and train movements (Eg) and (Bg) respectively of the gun. The mechanism is designed to compute the lateral deflection of the sight (Ds) in the inclined or slant plane of the gun and the vertical deflection of the sight (Us) and to drive dials 14 and 15 which respectively indicate these deflections. The dials 14 and 15 may comprise follow-the-pointer dials from which the setting may be applied manually to the sight or they may be connected to position the sight relative to the gun so as to maintain the computed lateral and vertical deflections automatically set on the sight.

More specifically, the elevation rack 10 drives an elevation shaft 20 by means of a pinion 21 and the train rack 11 drives a train shaft 30 by means of a pinion 31, shaft 32 and bevelled gears 33.

The train shaft 30 is connected by means of bevelled gears 34 and shaft 35 to position the rotary carriage 36 of a trigonometric integrator 40 of the single ball type. The carriage 36 is provided with teeth 37 which mesh with a pinion

2

38 connected to the shaft 35 for the above purpose. The carriage 36 carries a driving roller 41 which is driven through bevelled gears 42 by a shaft 43 which is driven by bevelled gears 44 from the shaft 45 of a constant speed motor 46.

The driving roller 41 of the integrator 40 drives a ball 47 which in turn drives a sine roller 48 and a cosine roller 49 at rates which are dependent upon the orientation of the axis of the driving roller 41 with respect to the axes of the rollers 48 and 49. The sine roller 48 is connected by shaft 50, bevelled gears 51, shaft 52 and bevelled gears 53 to drive a shaft 54 which in turn, through bevelled gears 55 and a shaft 56 drives one side 15 57 of a differential 58, the other side 59 of which drives a shaft 60 which is connected to one side 61 of a differential 62.

The cosine roller 49, through bevelled gears 70, shaft 71, bevelled gears 72, shaft 73 and bevelled gears 74, drives a shaft 75 which, through bevelled gears 76, shaft 77 and bevelled gears 78 drives the driving roller 79 of a second trigonometric integrator 80. The driving roller 79 of the integrator 80 is mounted on a carriage 81 which is positioned by teeth 82, pinion 83, shaft 84 and bevelled gears 85 from the elevation shaft 20. The driving roller 79 drives a ball 86 which in turn drives a sine roller 87. The sine roller 87 is connected by a shaft 88, bevelled gears 89, shaft 30 90 and bevelled gears 91 to drive the center of a differential 92.

The elevation shaft 20 also positions the carriage 95 of a third trigonometric integrator 96 by means of bevelled gears 97, shaft 98, pinion 99 and teeth 100 on the carriage 95. The carriage 95 carries a driving roller 101 which is driven through bevelled gears 102, shaft 103 and bevelled gears 104 from the train shaft 30. The driving roller 101 drives a ball 105 which, through a cosine roller 106, shaft 107 and bevelled gear 108 drives the center 109 of the differential 58.

The motor 46, through the shaft 45, bevelled gears 110 and shaft 111 drives the roller 112 of a rate integrator 113 of the two ball type which is provided with balls 114 mounted in a carriage 115 and connected to drive a disc 116. The carriage 115 is positioned by a shaft 120 by means of a pinion 121 and rack 122. The shaft 120 is provided with an adjusting knob 123 and with a worm 126 actuating a worm gear 127 to which is attached a dial 128.

The disc 116 is connected by teeth 130 and pinion 131 to drive a shaft 132 which is connected to bevelled gears 133, shaft 134 and pinion 135 55 meshing with teeth 136 and 137 on the circum-

ference of discs 138 and 139 respectively of the rate integrators 140 and 141 respectively. The integrator 140 is provided with balls 142 held in a carriage 143 which is positioned by a rack 144 and pinion 145 attached to a shaft 146. The shaft 146 is connected by bevelled gears 147 to a shaft 148 which positions the vertical deflection dial 15 by means of a worm 149 and a worm gear 150. The shaft 148 is also connected by bevelled gears 151, shaft 152, slip clutch 153, shaft 154 and bevelled gears 155 to drive the center 156 of a differential 157.

One side of the differential 157 is connected by a shaft 158 to be driven by the roller 159 of the integrator 140. The roller 159 is driven by the balls 142. The other side of the differential 157 is connected by a shaft 161 to one side of the differential 92. The other side of the differential 92 is connected by a shaft 162 and bevelled gear 163 to the center of a differential 164, one side of which is connected by a shaft 165 and bevelled gears 166 to the elevation shaft 20. The other side of the differential 164 is connected by a shaft 167 and bevelled gears 168 to the shaft 148.

The disc 139 of the integrator 141 drives balls 170 which in turn drive roller 171. The balls 170 are mounted in a carriage 172 which is positioned by a rack 173 and a pinion 174 mounted on shaft 175 and connected by bevelled gears 176 to a shaft 177 which is connected by a worm 178 and worm gear 179 to drive the lateral deflection dial 14. The roller 171 is connected by a shaft 180 to one side of a differential 181, the other side of which is connected by a shaft 182 and bevelled gear 183 to the center of the differential 62. The other side of the differential 62 is connected by a shaft 184 and bevelled gears 185 to the shaft 177. The center of the differential 181 is connected through bevelled gears 186, shaft 187, slip clutch 188, shaft 189 and bevelled gear 190 to the shaft 177.

The basic equations for the lateral and vertical deflections are as follows:

$$(1) \quad Ds = T(dBs - So \sin Bg) + k1$$

$$(2) \quad Us = T(dEs - So \cos Bg \sin Eg) + k2$$

in which Ds represents the lateral deflection of the sight in the slant plane of elevation of the gun, T represents time of flight of the projectile, dBs represents rate of train of the sight in the slant plane, So represents speed of the observer or own ship, Bg represents the angle of train of the gun in the horizontal plane, $k1$ is a constant representing drift, Us represents vertical deflection of the sight, dEs represents rate of elevation of the sight, Eg represents elevation of the gun and $k2$ is a constant representing super-elevation. The derivation of this formula is fully set forth in the co-pending application of James D. Tear and Charles W. Buckley, Serial No. 375,426, filed January 22, 1941.

The drift and super-elevation may be considered as constants for computers for use with gun of short range or these values may be computed from cams or other means. In this application these values are considered as the constants $k1$ and $k2$ and therefore may be taken care of by the setting of the mechanical connections of the apparatus.

Inasmuch as the train of the gun in the slant plane represents the train of the sight plus the lateral deflection and the elevation of the gun represents the elevation of the sight plus the

vertical deflection, the rates dBs and dEs may be represented as follows:

$$(3) \quad dBs = dBgS - dDs$$

$$(4) \quad dEs = dEg - dUs$$

where $dBgS$ represents the rate of train of the gun in the slant plane, dDs represents the rate of change of the lateral deflection (Ds), dEg represents the rate of change of the elevation of the gun (Eg), and dUs represents the rate of change of the vertical deflection (Us).

Substituting (3) and (4) in (1) and (2) and omitting the constants, the equations may be written as follows:

$$(5) \quad Ds = T(dBgS - dDs - So \sin Bg)$$

$$(6) \quad Us = T(dEg - dUs - So \cos Bg \sin Eg)$$

Transposing the T in each of these equations and expressing it as a rate dT , the equations become

$$(7) \quad Ds \times \frac{1}{dT} = dBgS - dDs - So \sin Bg$$

$$(8) \quad Us \times \frac{1}{dT} = dEg - dUs - So \cos Bg \sin Eg$$

These equations are solved by the above described apparatus in the following manner. The train and elevation of the gun (Bg) and (Eg) respectively are fed into the apparatus automatically in accordance with the movement of the gun carriage by the connections to the racks 11 and 10 respectively so that the positions of the shafts 30 and 20 represent the train (Bg) and elevation (Eg) of the gun and the rates of movement of shafts 30 and 20 represent the rate of train (dBg)

and the rate of elevation (dEg) respectively. The shaft 43 is driven by the motor 46 at a constant rate which may be considered to represent the speed of the ship (So) carrying the apparatus. For the purpose of this description the speed is assumed to remain constant. It is apparent however, that in case the speed of the own ship is subject to variation, a corresponding adjustment will be made in the speed of the shaft 43 by changing the ratio of the bevelled gears 44 or by introducing a variable ratio drive in the shaft 43, hence the shaft 43 may be considered to rotate at a rate representing the speed of the ship (So) and to drive the driving roller 41 of the integrator 40 at a corresponding rate.

The shaft 35 which is connected to the shaft 30 maintains a position corresponding to the angle of the train of the gun (Bg) and causes the carriage 36 of the trigonometric integrator 40 to take a corresponding position. The movement transferred to the roller 48 represents the sine function of the position of the carriage 36 and therefore the sine of the angle of train of the gun (Bg), hence the shafts 52 and 54 are driven from the driving roller 41, ball 47 and roller 48 at a rate which represents $So \sin Bg$ and this rate is applied as an input to one side 57 of the differential 58.

The roller 49 of the trigonometric integrator 40 is positioned to represent a cosine function of the angular position of the carriage 36. Consequently the shafts 73, 75 and 77 are driven by the roller 49 at a rate which represents $So \cos Bg$. This rate is applied by the shaft 71 to the driving roller 79 of the second trigonometric integrator 80. The carriage 81 of this second integrator is positioned by the shaft 84 which in turn is connected to the elevation shaft 20 and takes a position representing gun elevation (Eg). The output of the trigonometric integrator 80 derived from the roller 87 accordingly represents $So \cos$

$Bg \sin Eg$ and this rate is applied by the shafts 88 and 90 to the center of the differential 92.

The rate of movement of this shaft 165 which is taken from the shaft 20 represents the rate of elevation of the gun (dEg). This is applied to one side of the differential 164. The rate of movement of the shaft 167 which is driven from the shaft 148 represent the rate of change of the vertical deflection (dUs), as will hereafter be explained.

The rate of movement of shaft 167 is applied to the other side of the differential 164. Hence the shaft 162 which is driven by the center of the differential 164 is driven at a rate corresponding to the difference of the two inputs ($dEg - dUs$). This rate is applied to one side of the differential 92. The center of the differential 92 as previously stated is driven at a rate representing $So \cos Bg \sin Eg$. Consequently, the shaft 161 which is driven from the other side of the differential 92 represents the difference between these two quantities, or $(dEg - dUs) - So \cos Bg \sin Eg$ which quantity represents the righthand side of the Equation 8. The integrator 140 is connected to act as a tachometer to measure this rate of rotation of the shaft 161.

The roller 112 is driven at a constant speed by the motor 46. The ball carriage in the integrator 113 is set in accordance with the time of flight (T) corresponding to the range which is set in by knob 123. The conversion from range to the time of flight may be made by appropriate graduation of the dial 128. This setting of the carriage 115 is such that the speed of rotation imparted to the disc 116 represents the reciprocal of the time of flight

$$\frac{1}{T}$$

hence the shaft 132 and discs 138 and 139 are driven at rates expressed as

$$\frac{1}{dT}$$

The balls 142 of the integrator 140 drive the roller 159 which in turn is connected to one side of the differential 151. Any movement of the center of the differential due to a difference in speeds of rotation of the shafts 158 and 161 is imparted to the shafts 154, 152, 148 and 146 to change the position of the ball carriage of the integrator 140. These shafts are connected to drive the ball carriage in a direction to increase or decrease the speed of rotation of the roller 159 as required to bring the rotation of the shaft 158 into synchronism with the rotation of the shaft 161 and thereby cause the center of the differential 151 to come to rest. If the position of the shaft 148 is assumed to represent the vertical deflection (Us) and the disc 138 rotates at a speed representing

$$\frac{1}{dT}$$

then the speed of the roller 159 represents

$$Us \times \frac{1}{dT}$$

which corresponds to the lefthand side of Equation 8. When the shafts 158 and 161 are rotating at the same rate, the conditions of Equation 8 are fulfilled and the position of the shaft 148 represents the vertical deflection (Us) and the rate of movement of the shaft 148 represents rate of change of vertical deflection (dUs).

The dial 15 which is driven by the shaft 148

accordingly represents the vertical deflection (Us). This quantity may be used to manually set the sight from the gun or may be applied to a shaft for setting the sight relative to the gun automatically as shown for example in the Chafee et al. Patent 2,206,875, dated July 9, 1940.

The rate of train of the gun in the inclined or slant plane ($dBgS$) is equal to the rate of train of the gun in the horizontal plane (dBg) time the cosine of the elevation of the gun (Eg) as set forth in the following equation:

$$(9) \quad dBgS = dBg \cos Eg$$

The shaft 103 which is driven by the shaft 30 rotates at a rate representing the rate of train of the gun (dBg). This rate is applied to the driving roller 101 of the trigonometric integrator 96. The carriage of this integrator is positioned by the shaft 98 which is connected to the elevation shaft 20 and accordingly takes the position representing the elevation of the gun (Eg). The ball 105 accordingly drives the output roller 106 of the integrator 96 at a rate representing $dBg \cos Eg$ which, as set forth in Equation 9 represents $dBgS$. This rate is applied to the center of the differential 58. One side of the differential 58 as above described, is driven by the shaft 56 at a rate representing $So \sin Bg$. The other side of the differential 58 is accordingly driven at a rate representing $dBgS - So \sin Eg$ and the shaft 60 applies this rate to one side of the differential 62.

The position of shaft 177 represents lateral deflection (Ds). Hence the rate of movement of the shaft 184 represents the rate of change of lateral deflection (dDs). This is applied to the lower part of the differential 62 and is subtracted from the movement imparted by the shaft 60. Hence the shaft 182 which is driven by the center of the differential 62 rotates at a rate corresponding to $dBgS - dDs - So \sin Bg$ which represents the righthand side of Equation 7. The speed of rotation of this shaft 182 is measured by the integrator 141 acting as a tachometer in the following manner:

The roller 171 and shaft 180 are driven from the disc 139 by the balls 170 which are positioned by the rack 173 and shafts 175, 177, 181, and 189 from the center of differential 181. These shafts are connected to cause the balls 170 to move to a position such that the roller 171 rotates at the same rate as the shaft 182. This position of the balls 170 which is represented by the position of the shaft 177 represents the lateral deflection (Ds). Since the disc 139 is rotated at a rate representing

$$\frac{1}{dT}$$

the rate of the roller 171 may be represented as

$$Ds \times \frac{1}{dT}$$

which corresponds to the lefthand side of Equation 7. When the shafts 180 and 182 are rotating at the same rate the conditions of Equation 7 are satisfied and the position of the shaft 177 represents the lateral deflection (Ds) of the sight from the gun in the slant plane. This deflection may be set into the sight manually or automatically as set forth in the Chafee et al. patent above identified.

In the above described operation of integrators 140 and 141 the equated quantities are represented by the rates of rotation of the various shafts. Hence the actual angular positions of the 75 shafts representing the equated quantities are un-

important and have no effect on the accuracy of the results. The slip clutches 153 and 188 prevent the ball carriages from overrunning their limiting positions under extreme conditions. These slip clutches do not affect the accuracy of the result because as pointed out above the relative angular positions of the various shafts equated by differential 157 and 181 do not enter into the computation.

Although a specific embodiment of the invention has been shown for purposes of illustration, it is to be understood that the invention is capable of various uses and that changes and adaptations may be made therein as will be readily apparent to a person skilled in the art. The invention is only to be limited in accordance with the scope of the following claims.

What is claimed is:

1. Apparatus for calculating the vertical deflection of a sight from a gun or the like, comprising an elevation input shaft settable in accordance with the elevation of the gun (Eg), a train input shaft settable in accordance with the train of the gun in a horizontal plane (Bg), a time-of-flight input shaft settable in accordance with the time of flight of the projectile (T), a rotatable shaft, means driving said rotatable shaft at a rate representing the own ship speed (So), a trigonometric integrator having an input member driven by said rotatable shaft and having a second input member positioned by said train shaft and having means driving an output member at a rate representing So cos Bg, a second trigonometric integrator having an input member driven by said last output member and having a second input member positioned by said elevation input shaft and having means driving an output member at a rate representing So cos Bg sin Eg, an output shaft positionable to represent the computed vertical deflection of the sight (Us), a differential having input members driven by said elevation shaft and said output shaft respectively, and having an output member driven at a rate representing dEg - dUs, a second differential having an input member driven by said last output member and having a second input member driven by the output member representing So cos Bg sin Eg and having an output member driven at a rate representing dEg - dUs - So cos Bg sin Eg, a rate integrator having a rate input member positioned by said time of flight shaft to represent time of flight (T) and having a second input member driven at a constant rate and having an output member driven thereby at a rate representing

$$\frac{1}{dT}$$

a second rate integrator having an input member driven by said last output member and having a rate input member positioned by the output shaft representing the vertical deflection (Us) and having means driving an output member at a rate representing

$$Us \times \frac{1}{dT}$$

and means positioning the vertical deflection output shaft and the rate input member of said last integrator to cause said last output member to be driven at a rate corresponding to the rate of the output member of said second differential.

2. Apparatus for calculating the lateral deflection of a sight from a gun or the like, comprising an elevation input shaft settable in accordance with the elevation of the gun (Eg), a train input

shaft settable in accordance with the train of the gun in a horizontal plane (Bg), a time of flight input shaft settable in accordance with the time of flight of the projectile (T), a rotatable shaft, means driving said rotatable shaft at a rate representing the own ship speed (So), a trigonometric integrator having an input member driven by said rotatable shaft and having a second input member positioned by said train

10 shaft and having means driving an output member at a rate representing So sin Bg, a rate integrator having a rate input member positioned by said time of flight shaft to represent time of flight (T) and having a second input member

15 driven at a constant rate and having means driving an output member at a rate representing

$$\frac{1}{dT}$$

20 a second trigonometric integrator having an input member driven by the train input shaft at a rate representing the rate of train of the gun (dBg) and having a second input member positioned in accordance with the elevation of the gun (Eg) and having means driving an output member at a rate representing dBg cos Eg which equals the rate of train of the gun in its normal plane (dBgS), a differential having one input member driven by said last output member and having a second input member driven by the output member driven at a rate representing So sin Bg and having an output member driven at a rate representing dBgS - So sin Bg, an output shaft positionable to represent the lateral deflection of the sight (Ds), a second differential having input members driven by said last output member and by said output shaft respectively and having an output member driven thereby at a rate representing dBgS - Ds - So sin Bg, a second rate integrator having an input member driven by said

$$\frac{1}{dT}$$

45 output member and a rate input member positioned by said output shaft and having means driving an output member at a rate representing

$$Ds \times \frac{1}{dT}$$

50 and means positioning the lateral deflection output shaft and the rate member of said second rate integrator to cause the output member of said second rate integrator to be driven at a rate corresponding to the rate of the output member of said second differential.

3. Apparatus for calculating the deflection of a sight from a gun or the like, comprising an elevation input shaft settable in accordance with the elevation of the gun (Eg), a train input shaft settable in accordance with the train of the gun in a horizontal plane (Bg), a time of flight input shaft settable in accordance with the time of flight of the projectile (T), a rotatable shaft, means driving said rotatable shaft at a rate representing the own ship speed (So), a trigonometric integrator having an input member driven by said rotatable shaft and having a second input member positioned by said train shaft and having

60 means driving output members at rates representing So sin Bg and So cos Bg respectively, a second trigonometric integrator having an input member driven by said output member representing So cos Bg and having a second input

70 member positioned by said elevation input shaft

2,430,108

9

and having means driving an output member at a rate representing $So \cos Bg \sin Eg$, an output shaft positionable to represent the computed vertical deflection of the sight (Us), a differential having input members driven by said elevation input shaft and said output shaft respectively, and having an output member driven at a rate representing $dEg - dUs$, a second differential having an input member driven by said last output member and having a second input member driven by the output member representing $So \cos Bg \sin Eg$ and having an output member driven at a rate representing

$$dEg - dUs - So \cos Bg \sin Eg$$

a rate integrator having a rate input member positioned by said time of flight shaft and having a second input member driven at a constant rate and having means driving an output member at a rate representing

$$\frac{1}{dT}$$

a second rate integrator having an input member driven by said first rate integrator output member and having a rate input member positioned by the output shaft representing the vertical deflection (Us) and having means driving an output member at a rate representing

$$Us \times \frac{1}{dT}$$

and means positioning the vertical deflection output shaft and the rate input member of said second rate integrator to cause its output member to be driven at a rate corresponding to the rate of the output member of said second differential, a third trigonometric integrator having an input member driven by the train input shaft at a rate representing the rate of train of the gun (dBg) and having a second input member positioned in accordance with the elevation of the gun (Eg) and having means driving an output member at a rate representing $dBg \cos Eg$ which equals the rate of train of the gun in the slant plane ($dBgS$), a third differential having one input member driven by the output member of said third integrator and having a second input member driven by the output member representing $So \sin Bg$ and having an output member driven at a rate representing $dBgS - So \sin Bg$, a second output shaft positionable to represent the lateral deflection of the sight (Ds), a fourth differential having input members driven by the output member of the third differential and by said second output shaft respectively and having an output member driven at a rate representing

$$dBgS - dDs - So \sin Bg$$

a third rate integrator having an input member driven by said

$$\frac{1}{dT}$$

output member and having a rate input member positioned by said second output shaft and having means driving an output member at a rate representing

$$Ds \times \frac{1}{dT}$$

and means positioning the second output shaft and the rate member of said last integrator to cause the output member of said third rate integrator to be driven at a rate corresponding to

10

the rate of the output member of said fourth differential.

4. Apparatus for calculating the vertical deflection of a sight from a gun or the like, comprising an elevation input shaft settable in accordance with the elevation of the gun (Eg), a train input shaft settable in accordance with the train of the gun in a horizontal plane (Bg), a time of flight input shaft settable in accordance with the time of flight of the projectile (T), a rotatable shaft, means driving said rotatable shaft at a rate representing the own ship speed (So), a trigonometric integrator having an input member driven by said rotatable shaft and having a second input member positioned by said train shaft and having means driving an output member at a rate representing $So \cos Bg$, a second trigonometric integrator having an input member driven by said last output member and having a second input member positioned by said elevation input shaft and having means driving an output member at a rate representing $So \cos Bg \sin Eg$, a second rotatable shaft, means operable by said elevation input shaft to rotate the said second rotatable shaft at a rate representing the rate of elevation of the gun (dEg), a shaft driven to represent the rate of change of the computed vertical deflection of the sight (dUs), a third rotatable shaft driven at a rate which is a function of the combined rates of said second rotatable shaft, said dUs shaft and said last output member and which represents $dEg - dUs - So \cos Bg \sin Eg$, and rate measuring means including an output member positioned as a function of the combined rates of said third rotatable shaft and the setting of said time of flight shaft to represent $T (dEg - dUs - So \cos Bg \sin Eg)$ which equals the vertical deflection of the sight from the gun.
5. Apparatus for calculating the vertical deflection of a sight from a gun or the like, comprising an elevation input shaft settable in accordance with the elevation of the gun (Eg), a train input shaft settable in accordance with the train of the gun in a horizontal plane (Bg), a time of flight input shaft settable in accordance with the time of flight of the projectile (T), a rotatable shaft, means driving said rotatable shaft at a rate representing the speed of the own ship (So), a trigonometric integrator having an input member driven by said rotatable shaft and a second input member positioned by said train shaft and having means driving an output member at a rate representing $So \cos Bg$, a second trigonometric integrator having an input member driven by said last output member and a second input member positioned by said elevation input shaft and having means driving an output member at a rate representing $So \cos Bg \sin Eg$, a second rotatable shaft, means driving said second rotatable shaft at a rate representing the rate of elevation of the gun (dEg), a shaft driven to represent the rate of change of the computed vertical deflection of the sight (dUs), a third rotatable shaft driven at a rate which is a function of the rate of said second rotatable shaft and of said last output member and which represents $dEg - dUs - So \cos Bg \sin Eg$, a fourth rotatable shaft, means driving said fourth rotatable shaft at a rate representing

$$\frac{1}{dT}$$

and rate measuring means including an output member positioned as a function of the combined

rates of said third and fourth rotatable shafts to represent $T (dEg - dUs - So \cos Bg \sin Eg)$ which equals the vertical deflection of the sight from the gun.

6. Apparatus for calculating the lateral deflection of a sight from a gun or the like, comprising an elevation input shaft settable in accordance with the elevation of the gun (Eg), a train input shaft settable in accordance with the train of the gun in a horizontal plane (Bg), a time of flight input shaft settable in accordance with the time of flight of the projectile (T), a rotatable shaft, means driving said rotatable shaft at a rate representing the speed of the own ship (So), a trigonometric integrator having an input member driven by said rotatable shaft and a second input member positioned by said train shaft and having means driving an output member at a rate representing $So \sin Bg$, a second trigonometric integrator having an input member driven by said train input shaft and a second input member positioned by said elevation input shaft and having means driving an output member at a rate representing $dBg \cos Eg$ which represents the rate of train of the gun in the slant plane (dBgS), a second rotatable shaft driven by said dBgS output member, a third rotatable shaft, differential means driving said third rotatable shaft at a rate which is a function of the rates of said second rotatable shaft and of said So sin Bg output member which rate represents $dBgS - So \sin Bg$, a fourth rotatable shaft positionable to represent the computed lateral deflection (Ds), a fifth rotatable shaft, differential means driving said fifth rotatable shaft at a rate which is a function of the combined rates of said third and fourth shafts which rate represents $(dBgS - dDs - So \sin Bg)$, rate measuring means including means positioning an output member as a function of the rate of said fifth rotatable shaft and of the setting of said time of flight input shaft to represent $T (dBgS - dDs - So \sin Bg)$ which equals the lateral deflection of the sight (Ds), and means actuated by said last output member to drive said fourth rotatable shaft at a rate representing the change of lateral deflection (dDs).

7. Apparatus for calculating the lateral deflection of a sight from a gun or the like, comprising an elevation input shaft settable in accordance with the elevation of the gun (Eg), a train input shaft settable in accordance with the train of the gun in a horizontal plane (Bg), a time of flight input shaft settable in accordance with the time

of flight of the projectile (T), a rotatable shaft, means driving said rotatable shaft at a rate representing the speed of the own ship (So), a trigonometric integrator having an input member

- 5   member driven by said rotatable shaft and having a second input member driven by said train shaft and having means driving an output member at a rate representing $So \sin Bg$, a second trigonometric integrator having an input member driven by said train input shaft and a second input member positioned by said elevation input shaft and having means driving an output member at a rate representing $dBg \cos Eg$, which represents the rate of train in the slant plane (dBgS), a 10   15   second rotatable shaft driven by said dBgS output member, a third rotatable shaft driven at a rate which is a function of the combined rates of said second rotatable shaft and of said So sin Bg output member which rate represents $dBgS - So \sin Bg$, a fourth rotatable shaft positionable to represent the computed lateral deflection (Ds), a fifth rotatable shaft, differential means driving said fifth rotatable shaft at a rate which is a function of the combined rates of said third and fourth 20   25   shafts which rate represents $dBgS - dDs - So \sin Bg$, a sixth rotatable shaft, means controlled by said time of flight input shaft to drive said sixth rotatable shaft at a rate representing

30       $\frac{1}{dT}$ and rate measuring means including means positioning an output member as a function of the rates of said fifth and sixth rotatable shafts to 35   represent $T (dBgS - dDs - So \sin Bg)$ which equals the lateral deflection of the sight (Ds) from the gun, and means actuated by said Ds output member to drive said fourth rotatable shaft at a rate representing the change of lateral deflection (dDs).
